SEALING MACHINE

Emerson E. Hogg, New Kensington, Pa., assignor
to Aluminum Company of America, Pittsburgh,
Pa., a corporation of Pennsylvania

Application March 14, 1938, Serial No. 195,697

3 Claims. (Cl. 226—86)

This invention relates to sealing machines, and relates particularly to apparatus for the affixation of plug closures to containers.

5 Plug closures of the type to which I refer are shallow, cup-like shells that have associated therewith a sealing gasket and are affixed within the mouth of a container by expansion.

10 Various sealing machines have in the past been developed to affix such closures, and, in general, the sealing heads of these machines have been characterized by closure expansion means including a plurality of segments. Such segments in several of the known sealing heads have consisted of slit portions of a tubular member, which portions are flexed outwardly by suitable means to expand and affix a closure. It is apparent that to permit easy flexing such segments are characterized by considerable length so that the sealing head of which the slit member forms 15 a part is necessarily large.

20 Sealing heads have also been developed in which the expansion members are forced radially outwardly in sliding contact with a flat bearing surface by a suitably shaped cam member which also slides in contact with the expansion members. These heads consequently are characterized by frictional losses which lower their 25 mechanical efficiency.

25 The principal object of this invention is that of providing a compact and efficient sealing head for affixing plug closures. Related thereto is the object of providing a sealing head having oscillatable closure expansion members pendentially arranged to permit actuation thereof in a manner entailing relatively low frictional losses of applied force. In addition, it is an object to provide an arrangement of the aforesaid expansion means and actuating means utilizing a lever-like 30 mechanical advantage to effect an additional reduction of the applied force required to affix a closure. Furthermore, it is an object to provide sealing apparatus having the foregoing advantages that is adaptable to use in either manually operated or power-driven machines.

40 These and other objects related thereto will be more fully understood when considered in the light of the following description of the accompanying drawing, in which:

45 Fig. 1 is a central vertical sectional view of sealing apparatus illustrative of my invention, showing the operating cam in uppermost relative position;

50 Fig. 2 is a sectional view taken on the line 55 II—II of Fig. 1;

Fig. 3 is a vertical view, partly in section, illustrative of the apparatus of Fig. 1, but showing the operating cam in lowermost relative position;

Fig. 4 is a perspective view of a closure expansion member.

The apparatus comprises a centrally apertured housing 1 that has an annular top flange 2 and an annular bottom flange 3, the bottom flange being provided interiorly and exteriorly with 10 screw threads. Within the recess formed by the bottom flange 3 and major portion of the housing 1 are segments 4 pendentially arranged upon an unyielding or rigid annular support 5. The support is provided with threads by means of 15 which it is attached to the threaded flange 3.

A cylindrical cam 6 extends through the housing 1, and this member, together with a continuous annular spring 7, maintains the segments 4 in circumferential arrangement with respect to both itself and the support 5. The upper end of the cam 6 is provided with a shoulder 8 and is suitably recessed to accommodate a shaft 9 to which the cam is attached as by a set screw 10 that is threaded into the shoulder 8. The screw 10 projects through a slot 11 in the flange 2 to support the housing and the parts attached thereto.

The details of segment shape and manner of support that make possible the movement of the segments upon movement of the cam 6 relative thereto, or vice versa, will now be described in more detail. The support 5 has an inwardly directed flange that is provided with an annular peripheral portion 13. Extending from the top surface of the support flange to a chamfered edge portion 14, the peripheral portion 13 is convexly arcuate in cross-section and constitutes a substantially semi-toroidal portion forming a bearing surface for the segments 4 which are suspended therefrom upon shoulders 15. The shoulder 15 of each segment, which is a plane surface, forms with the adjoining segment portion an angle of less than 90° adapted to permit a suitable range of oscillation of the segments without binding against the surfaces of adjacent parts. Preferably this is obtained by an angle of less than 90° adapted to permit the desired range of oscillation about the fixed center of rotation provided by the support 5 in an arc concentric with the arcuate cross-section of the peripheral portion 13. In addition, in order to permit such free oscillations of the segments, the surface of each segment facing the cylindrically shaped cam 55

6 must be of suitable contour and is preferably so shaped that, when in contact with the cam throughout the range of segment oscillation, it is complementary thereto. To prevent binding 5 of the segments against each other, each segment at its upper end is suitably relieved, as indicated at 16. Near the lower end of each segment 4 a projection 17 adapted to contact the cam 6 is provided whereby relative movement between the 10 cam and segments actuates the latter. The exterior surfaces of the lower ends of the segments 4, which upon actuation of the segments contact and expand the closure to be affixed, may be smooth, as shown, or provided with suitable 15 configurations to produce expanded portions of desired size and shape.

To guide a container such as that fragmentarily shown in Fig. 1, a guide member 18 is provided which is adjustably attached as by 20 means of threads to the flange 3. This guide member has a flaring mouth 19 which leads to a suitably shaped seat 20 adapted to receive the mouth of the container to be sealed. A large jam 25 nut 21 locks the guide member 18 in desired position on the housing 1.

In the operation of this apparatus, suitable 30 movement of the segments 4 and the cam 6 relative to each other from the respective positions shown in Fig. 1, causes the cam to advance along 35 the adjoining inclined surfaces of the projections 17 to the respective positions such as those shown in Fig. 3, so that the segments oscillate about the fixed support 5 and have their lower ends forced outwardly against a shell 22, which 40 motion expands and deforms the shell against the sealing gasket 23 to retain frictionally the shell and gasket forming the closure within the mouth of the container. Upon withdrawal of the cam 6 from actuating contact with the projections 45 17, the spring 7 returns the segments to their normal position. In connection with the foregoing relative movement between the segments 4 and cam 6, the upper end of the slot 11 serves as a stop by contacting the screw 10, or vice versa, depending upon the manner of creating such movement.

From the foregoing description, it is apparent 50 that the pendent segments 4 are at all times retained in circumferential suspension from the support 5 by the cam 6; that they have at any given position only line contact with the arcuate bearing surface of the support 6, so that the applied power lost in overcoming friction between the segments and their bearing surface is slight; 55 and, since the shape of the inner faces of the segments with respect to the cam 6 permits the segments to roll against the cam upon relative movement of the cam and segment projections 17 while in actuating contact, that frictional losses are further reduced. Moreover, the mechanical advantage accompanying the suspension of the segments at their upper ends and application of actuating force against their lower ends, should now be apparent.

Numerous modifications of the embodiment by which I have chosen to illustrate my invention can be made depending upon the circumstances of use. For instance, in the sealing of glass containers, it may be found desirable to provide an 5 elastic seat pad, made of rubber for example, to support the exterior container mouth portion to reduce breakage. The addition of such a pad together with a connection of the head to an evacuating means and the few changes necessary to 10 hermetically seal the head creates a highly efficient vacuumizing unit characterized by an extremely small vacuumizing chamber within the head. Thus, it is to be understood that numerous 15 modifications and embodiments come within my inventive concept; and with the intent, therefore, to include all modifications and embodiments coming within that concept, I claim:

1. In a machine for affixing closures to containers, a rigid annular support having a semi-toroidal edge portion, a plurality of oscillatable closure expansion means carried solely by said support, and means for actuating said expansion means, each of said expansion means being suspended between said support and said actuating 20 means by an outwardly extending end shoulder, said shoulder bearing tangentially against said semi-toroidal edge portion and maintaining line contact therewith throughout the operative arc 25 of said expansion means, whereby said arc has a 30 constant radius.

2. In a machine for affixing closures to containers, a rigid annular support having a semi-toroidal edge portion, a plurality of oscillatable closure expansion means carried solely by said 35 support, and means for actuating said expansion means, each of said expansion means being suspended between said support and said actuating means by an outwardly extending end shoulder, said shoulder being a plane surface forming with 40 the adjoining surface of said expansion means an angle of less than 90° permitting said shoulder to bear throughout the operative arc of said 45 expansion means against such a portion of said semi-toroidal edge portion that said arc has a 50 constant radius.

3. In a machine for affixing closures to containers, a rigid annular support having a semi-toroidal edge portion, a plurality of oscillatable segments carried solely by said support, and a 55 cam, each of said segments being suspended between said support and said cam by an outwardly extending end shoulder and having a camming surface adapted to cooperate with said cam upon relative movement therebetween, said shoulder 60 being a plane surface forming with the adjoining surface of said expansion means an angle of less than 90° permitting said shoulder to bear throughout the operative arc of said 65 expansion means against such a portion of said semi-toroidal edge portion that said arc has a 70 constant radius.

EMERSON E. HOGG.
